UNITED STATES PATENT OFFICE.

ALBERT G. LARSON, OF PIEDMONT, AND EDWARD R. COOPER, OF SAN LEANDRO, CALIFORNIA; SAID COOPER ASSIGNOR TO JOSEPHINE W. COOPER, OF SAN LEANDRO, CALIFORNIA.

WASHING MACHINE MECHANISM.

Application filed October 15, 1925. Serial No. 62,532.

This invention relates to a washing machine mechanism and especially to improvements on the type of machine disclosed in the patent to Eric Lindberg entitled "Washing machine", Patent Number 1,523,027 issued January 13, 1925.

The washing machine illustrated in the patent above referred to is of a plunger type. A continuously operating driving shaft imparts a reciprocal and rotary movement to the plunger and only one reciprocal or plunger movement is obtained during each revolution of the driving shaft.

The object of the present invention is to generally improve and simplify the construction and operation of a machine of the character described, and particularly to provide a mechanism whereby the rotary movement of the drive shaft is transmitted to oscillate the plunger and simultaneously transmit two reciprocal movements to the plunger during each revolution of the drive shaft.

One form which our invention may assume is described in the following specification and illustrated in the accompanying drawings, in which—

Fig. 1 is a sectional view of a wash tub showing the washing machine and the driving mechanism in side elevation.

Fig. 2 is a cross section taken on line II—II of Fig. 1.

Referring to the drawings in detail and particularly to Fig. 1, A indicates a wash tub of any suitable nature. Supported by the upper edge of the tub is a base plate B, and supported by the base plate is an electric driving motor 2, a gear reduction mechanism 3, and a rocker shaft 4. The base plate is in this instance hingedly secured to one edge of the tub as shown at 5 and it also forms a cover for the tub. The center portion of the base plate is raised to form an auxiliary housing generally indicated at C, and this raised portion has a journal member formed in one side wall as at 6 in which the rocker shaft 4 is journaled. Secured on the outer end of the rocker shaft is a comparatively short crank arm 7 to which a rocking movement is transmitted through means of a connecting rod 8. The reduction gear 3 drives the shaft 9 and a crank arm is secured to the shaft as indicated at 10. The other end of the connect-

ing rod is connected with this crank arm 55 and the continuous rotation of the crank arm 10 transmits a rocking movement to the arm 7 and the shaft 4. Secured to the inner face of the base plate or cover member B and extending downwardly therefrom is a 60 bracket 11 which carries a bearing member 12. Journaled in this bearing is a rocker shaft 13 on the outer end of which is formed a rocker bearing 14. Reciprocally mounted in the rocker bearing is a shaft or rod 15 65 and secured on the lower end thereof is a plunger cup 16. Secured on the upper end of the rod is a head member 17. Carried by the head is a pin 18 and connected therewith is a crank arm 19 which is secured at 70 its upper end to the rocker shaft 4 as indicated at 20.

The operation of the mechanism will be as follows: A continuous rotation is transmitted to the shaft 9 through the electric motor 2 and the gear reduction 3. This continuous rotation transmits a rotary movement to the crank 10, and this in turn transmits a rocking movement to the cranks 7 and 19 through the connecting rod 8 and the rocker shaft 4. The head member 17 is secured on the upper end of the plunger shaft 15 and as the lower end of the crank arm 19 is pivotally attached thereto an oscillating movement will be transmitted to shaft 15 and the 80 plunger cup 16 and two reciprocal movements will always be transmitted during each revolution of the driving shaft 9. This is a decided advantage when comparison is made with the former patent referred to as the 85 efficiency of the washing mechanism is substantially doubled. The two reciprocal movements imparted to the plunger cup will, as previously stated, take place during each revolution of the shaft 9. This is due to 90 the fact that the crank arms 7 and 19 rock or oscillate while the crank 10 rotates. When crank 10 assumes the position shown at 10, crank arms 7 and 19 assume dotted line position indicated at 7^a and 19^a, and the 95 plunger shaft and plunger assume the dotted line position indicated at 15^a and 16^a; when crank 10 assumes the dotted line position indicated at 10^b, the position of the cranks 7 and 19 is reversed, and the plunger shaft 100 and cup assume the dotted line position indicated at 15^b and 16^b; and when crank 10 assumes either of the dotted line positions 105

shown at 10^b and 10^c, shaft 15 and plunger 16 assume the full line position shown in Fig. 1. It is for this reason that an oscillating movement is transmitted to the plunger 5 and two reciprocal movements are simultaneously produced during each single revolution of the drive shaft 9.

Having thus described our invention, what we claim and desire to secure by Letters 10 Patent is—

1. In a washing machine of the character described, a supporting member, a driving motor, a continuously operating driving shaft driven by the motor, a rocker shaft 15 journaled on the support, means for transmitting a rocking movement from the drive shaft to said rocker shaft, a reciprocally mounted plunger also carried by the support, and means whereby a reciprocal and a 20 simultaneous oscillating movement in a vertical plane is transmitted from the rocker shaft to the plunger.

2. In a washing machine of the character described, the combination with the plunger 25 and the rod supporting the same of a driving mechanism therefor, the said mechanism comprising a rocker shaft, means for transmitting a rocking movement thereto, a crank arm on the shaft, a head member secured to the plunger rod and pivotally connected with the crank arm, a pivotally mounted bearing 30 in which the plunger rod is adapted to reciprocate and oscillate in a vertical plane.

3. In a washing machine of the character 35 described, the combination with the plunger and the rod supporting the same of a driving mechanism therefor whereby a simultaneous reciprocal and oscillating movement is transmitted, said mechanism comprising an upper and a lower stationary bearing, a rocker shaft journaled in the upper bearing, a pivoted guide bearing mounted in the lower bearing, said plunger rod extending through said pivoted bearing and being guided thereby 40 during its reciprocal and vertical oscil-

lating movement, a head member secured to the plunger rod, a crank arm secured to the rocker shaft, a pin on the head member forming a pivotal connection between the head member and the crank arm and means for 50 transmitting rocking movement to the rocker shaft.

4. In a washing machine of the character described, a rod and a plunger mounted on the lower end thereof, a bracket, a pivotally 55 mounted bearing member in the bracket in which the rod and plunger are adapted to reciprocate, a rocker shaft journaled in the bracket above the pivotally mounted bearing, a crank arm on one end of the shaft, a 60 driving shaft, a crank arm thereon, a link connecting the first named crank and the second named crank and adapted to transmit a rocking movement to the rocker shaft, a second crank arm on the rocker shaft, a 65 bearing member pivotally mounted in the swinging end of said last named rocker arm, and a connection formed between said bearing and the plunger rod.

5. In a washing machine of the character 70 described, a rod and a plunger mounted on the lower end thereof, a bracket, a pivotally mounted bearing member in the bracket in which the rod and plunger are adapted to reciprocate, a rocker shaft journaled in the 75 bracket above the pivotally mounted bearing, a crank arm on one end of the shaft, a driving shaft, a crank arm thereon, a link connecting the first named crank and the second named crank and adapted to transmit a rocking movement to the rocker shaft, a second crank arm on the rocker shaft, a 80 bearing member pivotally mounted in the swinging end of said last named rocker arm, and an adjustable connection formed between 85 said bearing and the plunger rod permitting vertical adjustment of the plunger rod and plunger.
